UNITED STATES PATENT OFFICE.

DAVID A. EBINGER, OF COLUMBUS, OHIO.

SEAT STRUCTURE FOR LATRINES.

1,170,741.

Specification of Letters Patent. Patented Feb. 8, 1916.

Application filed November 11, 1912. Serial No. 730,572.

To all whom it may concern:

Be it known that I, DAVID A. EBINGER, a citizen of the United States, residing at Columbus, in the county of Franklin and State 5 of Ohio, have invented certain new and useful Improvements in Seat Structures for Latrines, of which the following is a specification.

My invention relates to seat structures for 10 latrines and is particularly directed in an endeavor to present a structure fulfilling all modern sanitary requirements. It frequently happens that structures such as this, especially those used in public comfort stations 15 and other public places, become soiled through carelessness or otherwise. The present invention is an endeavor to eliminate this as much as is possible. This I do by the provision of a base member having an 20 opening therein and having cut out portions at its rear and front, thus doing away with that portion of the structure which is usually soiled. Mounted upon each side of the opening I form the seat of two members, 25 concaved in the usual manner, and spaced from each other. In doing this, I have not only eliminated a portion of the material usually soiled, but I have also formed my structure so that this eliminated portion is 30 not in actual use.

A further object of my invention is to form a seat structure that may be readily swung upon its hinges and not be subject to sticking or breaking caused by the usual 35 swelling of some moisture absorbent material used in its construction. I have made my base member of metal and formed the seat of the usual wooden type rigidly mounting the same upon the base in any preferred 40 manner. In making the seat of a segmental nature, I have decreased the surface space used for mounting the same, in the sense that each board occupies a less surface than a seat board made of one entire piece. I 45 have found that by making the seat board of one entire piece, it has been difficult to prevent its warping out of shape with the possible breaking, and not even by the use of an increased number of screws, can it be 50 done. By reducing the amount of contacting surface on one member, this mounting can be much more readily accomplished.

The preferred embodiment of my invention is shown in the accompanying drawings, in which similar characters of refer-

ence designate corresponding parts, and in which:

Figure 1 is a plan view of my improvement shown in connection with a latrine, Fig. 2 is a plan view of the seat structure 60 separately, and, Fig. 3 is a section taken on line 3—3 of Fig. 2.

The numeral 1 designates any common type of latrine having a vent hood 2 communicating with an outlet passageway 3. 65 Pivotedly mounted upon the latrine as at 4 is a seat 5 preferably made of metal or some other non-moisture absorbent material and having an opening 5^a therein. At the front and rear of this opening I have provided 70 cut-out portions 6 and 7, the purpose of which will be hereinafter more fully stated. Mounted upon each side of the opening 5^a are concaved seat boards 8 which conform in a general manner to the contour of the 75 opening. Carried in superposed relation is a lid structure 9 pivoted as at 10 to the base member 5. During the normal occupancy, the cut-out portions 6 and 7 are those portions which usually become soiled and, of no 80 particular use, I have eliminated them. These cut-out portions not only serve for this purpose, but, being never fully covered, a draft is created from the outside air through the vent passageway 3. The seg- 85 mental seat boards 8 being mounted upon the base member 5 and spaced from each other, they will also space the occupant from the base member 5 should, by any chance, this member become soiled. It will be un- 90 derstood that the segmental seat boards may be made in a variety of shapes and yet fulfil all the objects of my invention.

What I claim, is:

1. A liftable latrine seat structure comprising a metal base having an opening 95 therein, and a wooden seat rigidly mounted on said base and conforming substantially to the contour of said opening, said seat being of greatly reduced area in comparison 100 with said base.

2. A liftable latrine seat structure comprising a substantially rectangular non-ab- 105 sorbent base member having an opening therein, and a plurality of seat boards, said seat boards being rigidly mounted upon either side of said opening and having their adjacent ends spaced from each other and being of greatly reduced area with compari- 110 son with said base member.

3. A latrine seat comprising a unitary metallic base member having an opening therein, said opening having a supplemental cut-out portion at both its front and rear, 5 and a plurality of seat boards rigidly mounted upon either side of said opening and having their adjacent ends spaced from each other and on opposite edges of said cut-out portion, said seat boards being of greatly

reduced area in comparison with said base member.

In testimony whereof I affix my signature in presence of two witnesses.

DAVID A. EBINGER.
